UNITED STATES PATENT OFFICE

2,579,262

LEVEL LUFFING JIB CRANE

Ignatius Kay, London, England, assignor to The Wellman Smith Owen Engineering Corporation Limited, London, England, a company of Great Britain

Application April 30, 1947, Serial No. 745,033
In Great Britain May 3, 1946

1 Claim. (Cl. 212—8)

1

This invention relates to level luffing jib cranes and is concerned with modifications of the construction of crane forming the subject-matter of the invention described and claimed in the specification of the earlier United States Letters Patent No. 2,386,475 of October 9, 1945, to Kay.

According to the earlier invention, a level luffing jib crane comprises a frame, a balanced jib with free ends and a pivot intermediate such ends, connecting means between the jib and the frame constraining the said pivot to move in an arcuate path, further connecting means between the jib and the frame constraining a point on the jib offset from its longitudinal axis to move in a path directed substantially radially with respect to the said arcuate path, the said paths being such that the luffing of the jib produces substantially horizontal movement of its centre of gravity and substantially vertical movement of its end remote from the load, a pulley at the said jib-end, a second pulley on the frame substantially vertically beneath the first pulley and a hoisting rope passing from a winding drum on the frame over the second and first pulleys and over a hoisting pulley at the load-carrying end of the jib. In such a crane the hoisting rope pulls acting on the jib are arranged to have an equal moment about the centre of gravity of the jib, the ratio between the length of the jib forward of the said centre and the length of the remainder of the jib being equal to the ratio between the number of parts of hoisting rope at the rear jib-end and the number of parts of the same rope at the forward jib-end.

The connecting means between the jib and frame comprised a pair of links, each pivoted at one end to the frame and at the other end to the jib, so disposed that if extended beyond their pivots on the jib they would meet on the intersection of a transverse vertical plane containing the centre of gravity of the jib and a horizontal plane containing the rear jib-end. The upper link extended from a point on the frame horizontally opposite the centre of gravity of the jib to a point on the latter spaced both from the rear jib-end and from the centre of gravity by an amount equal to the length of the link, whereas the lower link extended from a point on the frame vertically beneath the rear jib-end to a point on the jib offset downwards from the point of attachment of the upper link to the jib, the distance between the two pivots on the jib being equal to the length of the upper link. For practical reasons, the said upper link was generally replaced by an equivalent but shorter link having

5 one end pivoted to the frame at a point lying on a line joining the pivot on the jib for the lower link to the point at which the frame-connected end of the upper link would otherwise be disposed. The shorter link extended in the direction of the intersection point for the upper and lower links (when extended) and was pivoted to the jib at a point lying on a line joining the jib-connected end of the lower link to the point at which the upper link would otherwise be connected to the jib.

10 In such cranes there is a point on the jib (referred to hereinafter as "the reference point") which subdivides the length of the jib into two parts, a head portion and a tail portion, the lengths of which bear the same relationship to each other as the number of parts of the hoisting rope at the tail of the jib bears to the number of parts of the same rope at the head of the jib. Hence, if there is one part of rope at both the head and the tail of the jib, the reference point is located mid-way of the length of the jib, whereas if there is one part of rope at the head and three parts at the tail, the reference point is located at one quarter of the length of the jib from the tail end thereof. The reference point in the cranes according to the said earlier invention has been constrained to move horizontally during the luffing of the jib (by reason of the linkage arrangements described) and it has therefore been considered essential to arrange that the centre of gravity of the jib should coincide with the said reference point, as will have become clear from the above brief description of the earlier invention. The path of travel of the reference point being horizontal, the rear jib-end was necessarily arranged to move vertically and the part or parts of hoisting rope extending from the pulley at this end to that on the crane frame was or were also vertically directed.

15 Now it frequently happens that the practical requirements in the construction of a level luffing jib crane make it inconvenient either to arrange the centre of gravity of the jib to coincide with the reference point or to arrange the pulley on the crane frame vertically beneath that on the rear jib-end. For example, in the earlier specification of United States Patent No. 2,386,475 there is shown and described a construction having the reference point located mid-way of the length of the jib. In a practical construction this would entail counterweighting the forward end of the jib or employing light metal in the construction of the rear end of the jib, or the use of 20 both expedients, in order to cause the centre of

gravity of the jib to coincide with the reference point.

The object of the present invention is to provide modifications in the said earlier invention which shall enable the effect of non-coincidence of the centre of gravity of the jib and the reference point to be overcome without such use of forward counterpoise or other undesirable expedient.

According to the invention, in a level luffing jib crane substantially in accordance with the invention claimed in the said earlier specification but having the centre of gravity of the jib disposed rearward of the reference point, the hoisting rope pulley at the tail-end of the jib is disposed so that a line joining the axis of the pulley to the reference point is canted upwards with relation to the line joining the reference point to the axis of the hoisting rope pulley at the head of the jib through a predetermined angle α , and the connecting means between the crane frame and the jib are arranged to cause the reference point to travel along a path inclined upwards and rearwards to the horizontal at an angle β which is equal to

$$\frac{n_1}{n+n_1} \alpha$$

where n is the number of parts of hoisting rope at the head of the jib and n_1 is the number of parts of the hoisting rope at the tail of the jib, so that the pulley at the tail-end will move along a path inclined downwards and rearwards to the vertical at the angle α and passing through the axis of a hoisting rope pulley mounted on the crane frame, the centre of gravity of the jib thereby being constrained to move horizontally.

The nature of the invention will be more clearly understood from the following description of some examples of the way in which it may be carried into effect and the theoretical considerations which apply, reference being made to the accompanying drawings which are mainly diagrammatic.

Fig. 1 is a line diagram illustrating the linkage arrangement which constitutes the main feature of the earlier invention referred to above and which is fully described in the specification of United States Patent No. 2,386,475.

Fig. 2 is a similar line diagram illustrating the modified arrangement of the present invention.

Fig. 3 is a diagrammatic side elevation of one form of crane embodying a practical example of the linkage arrangement shown in Fig. 2, there being one part of hoisting rope at the head and tail of the jib, and

Fig. 4 is a similar view of another form of crane according to the invention in which a different location of the reference point on the jib is necessitated by an alteration in the reeving of the ropes, there being one part of hoisting rope at the head of the jib and three parts of the same rope at the tail of the jib.

In Figs. 3 and 4 only the parts essential to a clear understanding of the present invention have been indicated, the main members of the jib being shown in heavy lines and the main members of the frame by double lines. Many of the bracing members and other known constructional details, including means permitting of slewing the crane or traversing it along rails when desired, have not been illustrated as their arrangement or construction will be obvious to those skilled in the art.

Referring first to the construction forming the subject-matter of the earlier United States Patent No. 2,386,475, shown in Fig. 1, a pivoted jib A, B (represented by its longitudinal centre-line) is suspended from a crane frame (not shown) by a pair of links, the pivotal point of the jib being at C. A downwardly extending arm D is rigidly fixed to the jib at the point C, is equal in length to the tail portion C2 of the jib, and has its lower end pivoted at E to the forward end of a thrust link F which has its rear end pivoted at C on the crane frame vertically beneath the end Z of the tail portion CZ. A second link H is pivoted at its upper end on the crane frame at a point J vertically above the tail end Z of the jib, is of a length equal to that of the arm D and is pivoted at its lower end to the jib at the point C. The links F and H, when extended, meet at the point K which during the movement is constantly vertically beneath a reference point L on the jib. The hoisting rope pulls acting on the jib A, B, are represented by the arrows M and N. The reference point is spaced from C by a distance equal to CZ and subdivides the jib into the head portion A and tail portion B. Due to the fact that the lengths of CZ, CL and CJ are all equal the angle ZJL is a right angle and the point J is horizontally opposite to the point L.

It has been demonstrated in the earlier specification referred to that luffing of the jib A, B, when thus supported from the crane frame, results in the reference point L always moving in a horizontal path, the tail end of the jib always moving in a vertical path, and the reduction or increase in the distance between the tail end of the jib and the point G always bearing a definite ratio to the lift or fall of the head end of the jib. The numerical value of this ratio depends on the relation between the lengths of the head and tail portions, A and B, respectively, of the jib and this relation is the same as that between the number of parts of hoisting rope at the tail of the jib and the number of parts of this rope at the head of the jib. With the center of gravity of the jib arranged to coincide with the reference point L and with the hoisting rope pulls, M and N, arranged to have an equal moment about the same point, the jib is in balance for any position of the point L along its horizontal path of travel. Moreover, the load supported from the head end of the jib A, B, will travel in a horizontal path during luffing of the jib, provided that the hoisting rope at the tail end of the jib runs vertically downwards to a pulley mounted on the crane frame at or near to the pivot G.

For practical constructional reasons it is preferred to replace the link H by an equivalent link O, this being pivoted on the crane frame at a point P lying on a line EJ and pivoted on the arm

60 D at a point Q lying on a line PK. The link H is removed when the link O is fitted.

As has been indicated above, it has heretofore been considered essential to arrange that the centre of gravity of the jib A, B, should coincide with the reference point L, and the part or parts of the hoisting rope extending from the tail end of the jib to the pulley on the crane frame was or were necessarily directed vertically. The rectangle JLKZ thus had its sides LK and JZ disposed vertically.

According to the present invention, the limitations and disadvantages of the earlier linkage arrangement may be removed by making some modifications therein, as shown in Fig. 2. In this figure, parts or points corresponding to those of

Fig. 1 are indicated by the same reference characters as have been used in describing Fig. 1.

The example chosen has the reference point L disposed mid-way of the length of the jib A, B, (the line B (or LY) representing the normal position of the tail portion) and the centre of gravity CG of the jib is disposed rearward of the reference point L. If the diagonal LZ (of the rectangle JLKZ) passing through the centre of gravity CG were to coincide with the continuation B of the upper part of the jib as in the construction of Fig. 1, luffing of this jib would cause the centre of gravity CG to rise and fall as the point L travelled horizontally. This is prevented with the construction of Fig. 2 in which the reference point L is arranged to move along a path LJ that is inclined upwards and rearwards with respect to the horizontal at an angle β such that the centre of gravity CG will always move along a horizontal path. The value of the angle β is readily determined by plotting the extreme positions of the jib (assuming horizontal movement of the reference point L), measuring the fall of the centre of gravity CG from the one position to the other, and then arranging for the reference point L to rise by a corresponding amount for the same displacement of the jib. The angle β is generally about 8° for cases where the reference point L is at the centre of length of the jib. Due to the inclination of the path LJ the rectangle JLKZ which fixes the positions of the points K and J is swung about its corner L through the angle β . The pivotal point C of the jib is now disposed on the second diagonal LZ of the rectangle (JK being the first diagonal) and this diagonal LZ inclines upwards with relation to the continuation B of the centre line of the upper part of the jib, at an angle β . The geometrical construction determining the positions and lengths of the links O and F and of the arm D is otherwise the same as in Fig. 1, the link D being shown as terminating at the line B for convenience but obviously being of the effective length EC.

Again due to the inclination of the path LJ, the rear jib-end no longer moves vertically nor does its extent of travel bear the constant definite relationship to the rise and fall of the head of the jib which is necessary to secure level luffing of the load. In order to secure this action, therefore, the hoisting rope pulley which would normally be disposed at the point Y on the tail portion of the jib is raised above the said point to an extent such that a line B¹ joining its axis X to the reference point L makes an angle α with the continuation B of the upper part of the centre line and is of the same length as said line B. The pulley now travels along a path (the disposition of which is shown by arrow N) also making an angle α with the vertical, as the jib is luffed. It can be demonstrated that the distance h travelled by the pulley along this path always bears a desired constant relationship to the vertical distance h^1 through which the head of the jib is displaced at the same time. For the example illustrated the distances h and h^1 are equal, as the number of parts of hoisting rope at the head and the tail of the jib are also the same.

The relation between the angles α and β is given by the expression

$$\beta = \frac{n_1}{n+n_1} \alpha$$

where n is the number of parts of rope at the

head of the jib and n_1 is the number of parts of rope at the foot of the jib. Where $n=n_1$ the angle β is half the angle α but when $3n=n_1$ the angle β is three-quarters of the angle α .

When a crane is being designed, the length of the jib is given and it is also known how many parts of rope there are to be at the head and tail ends thereof. Hence, the position of L is fixed. The approximate position of the centre of gravity of the jib is then calculated and the angle θ to be made with the horizontal by the jib at the position of maximum reach is then decided and the position for minimum reach is also selected.

The jib is then drawn in its two end positions assuming that the reference point L is moved horizontally and that the tail end of the jib is moved vertically. The vertical fall in the position of the centre of gravity in the movement from the one position to the other is then measured and the line joining the two locations of L is inclined upwards to the horizontal from the maximum reach position of L at an angle β such that L at the minimum reach position will have risen vertically through the same distance as the centre of gravity fell. An angle α is then calculated from

$$\beta = \frac{n_1}{h+n} \alpha$$

and the tail portion of the jib extending from the reference point L is inclined upwards at this angle α with respect to its original position. In addition, the pulley on the crane frame is positioned on a line making an angle α with the vertical from the new position of the tail end of the jib.

The rectangle JLKZ is then constructed with the side JL at an angle β to the horizontal and equal in length to the product of the length of the tail end of the jib and the cosine of the angle θ . The side LK is made equal to the product of the length of the tail end of the jib and the sine of the angle θ . The intersection of the diagonals of the rectangle fixes the position of the point C, and the appropriate position for the point C for the position of the jib in the minimum reach setting is also determined by drawing the jib with the diagonal LZ in the correct relative position and striking an arc from J with a radius JC to intersect LZ at C₁. Arcs are struck from C and C₁ with a radius JC and their intersection fixes the position of the point E. KE produced gives the direction of the link F which usually terminates on JZ produced. The position of Q is chosen on EC (generally as the result of practical experience) so that KQ produced will intersect JE at P appropriately close to the general position of the tail of the jib when at the maximum reach setting. The positions and lengths of the arm D and the links F and O are now fixed to give the correct motion of the jib, i. e., so that L will move along LJ and X will move in the direction N.

A practical form of construction of a crane corresponding to the diagram of Fig. 2 is illustrated by Fig. 3. Here the crane frame is indicated at W as being mounted on a rotatable platform X'' which may be driven in any suitable manner for slewing the crane and may in turn be mounted on rails in a manner permitting of the crane being displaced bodily. The parts of the crane which correspond to the elements of the diagram of Fig. 2 are indicated by the reference characters also used in that diagram. Only

the main outer members of the jib have been shown in heavy lines, the bracing members and other known constructional parts being omitted for clarity's sake. Additionally illustrated are a pulley R at the head of the jib, a pulley S at the tail-end of the jib, a load hook T, a run U of the hoisting rope extending from the pulley U¹ on the crane frame (to which the part N of the rope passes from the pulley S) to the winding drum V, and luffing gear comprising a screw Y'' pivotally attached at Y¹ to the link O and engaged in a motor-driven nut Z'' which is pivotally mounted at Z¹ on the crane frame W.

In operation, the jib is luffed by rotation of the nut Z''. The screw Y'' passes through the nut Z'' and thus draws the link O towards the pivot Z'. Since the point P is fixed on the frame, the movement of the link O towards the pivot Z' produces arcuate movement of the free end of the link O. The jib-pivot Q is at this free end and is thus moved arcuately when the nut Z'' is turned. The jib-pivot Q is rigidly connected to the arm D, which at its other end is pivoted at E to the forward end of a thrust link F, which in turn is pivoted at its rear end G to the frame. Thus the pivot E is constrained to move on an arcuate path having its centre at G. Since the link F is relatively long and the movement of the pivot E relatively short, this arcuate path approximates to a straight line normal to the link F, that is to say, along the line PE. The arcuate movement of the jib-pivot Q and the movement of the pivot E approximately along the line PE causes the arm D to pivot about E in an anticlockwise direction. Since the arm D is rigidly connected to the jib, this will also pivot about E in an anticlockwise direction, so that the pulley R at the head of the jib will swing upwards and inwards.

Owing to the construction of the crane and as explained in relation to the diagram of Fig. 2, the reference point L will move upwardly and inwardly along a line lying at an angle β to the horizontal, the tail-end of the jib will move downwardly towards the frame along a line lying at an angle α to the vertical, and the centre of gravity G will move inwardly along a horizontal line.

Fig. 4 shows another construction in which, as far as possible, corresponding parts are again indicated by like reference characters.

In this case, the centre of gravity of the jib (not indicated) is located somewhat lower down the jib than the reference point L which is itself at a distance from the pulley S of one-quarter of the length of the jib A, B, suitable counter-weighting being resorted to, as will be understood, but the counter-poise (not shown) being arranged on the canted up tail-end of the jib. Hence a single part M of the hoisting rope at the upper end R of the jib requires three parts of the same rope at the lower end S of the jib, and this is ensured by suitably reeving the rope, as shown at N¹, before it passes at U to the drum V. The operation of this crane is substantially as already described above, each of the three parts of rope N¹ releasing or taking up one third of the total rope required when the jib is luffed.

It is to be understood that the theoretically correct arrangement according to this invention is, as stated above, with the centre of gravity located on the diagonal LZ of the rectangle

JLKZ but in practice some slight departure from this condition is sometimes unavoidable due to manufacturing difficulties.

What I claim is:

5 A level luffing jib crane comprising a supporting frame, a balanced jib, a hoisting pulley at the load-carrying end of the jib, a first counter-loading pulley at the end of the jib remote from the load carrying end and so disposed that a line joining its axis to a point along the length of the jib located between the centre of gravity of the latter and the hoisting pulley is canted upwards through a predetermined angle α with relation to a line joining the said point to the axis of the said hoisting pulley, a pivot for the jib located between the said ends thereof, a second counter-loading pulley so located on the supporting frame beneath and rearwards of the first counter-loading pulley that a line joining 10 the axes of the counter-loading pulleys will make the angle α with the vertical, a winding drum on the said frame, a hoisting rope passed over said hoisting pulley and over said first and second counter-loading pulleys and attached to the said 15 winding drum, the number n of parts of the said rope at the load-carrying end of the jib bearing the same ratio to the number n_1 of parts of the said rope at the other end of the jib as the distance between the said point of the jib and the 20 said other end bears to the distance between the said point and the load-carrying end of the jib, means mounting the jib-pivot on the said frame for arcuate movement about a point thereon, a rigid part on the jib extending at an angle downwards away from the longitudinal axis of the 25 jib with its upper end proximate to the jib-pivot and its lower end spaced from the said jib-pivot by approximately the distance between the latter and the first counter-loading pulley, means 30 connecting the lower end of the said jib-part to the frame for movement substantially along a line joining the said lower end and the point on the frame about which the jib-pivot moves, and means for luffing the jib and thereby simultaneously producing displacement of both the 35 jib-pivot and the lower end of the said jib-part so that the said point in the length of the jib moves along a path inclined upwards and rearwards to the horizontal at an angle β which is 40 equal to

$$\frac{n_1}{n+n_1} \alpha$$

and the first counter-loading pulley moves along the line joining the axes of the two counter-loading pulleys, the centre of gravity of the jib thereby being constrained to move horizontally.
